UNITED STATES PATENT OFFICE.

WILLIAM H. LANE, OF WESTFIELD, NEW JERSEY, AND ALBERT V. T. DAY, OF NEW ROCHELLE, NEW YORK, ASSIGNEES, BY MESNE ASSIGNMENTS, TO HALL SWITCH & SIGNAL COMPANY, OF NEW YORK, N. Y., A CORPORATION OF MAINE.

ELECTRIC TRAFFIC-CONTROLLING SYSTEM FOR RAILROADS.

1,099,259.

Specification of Letters Patent.

Patented June 9, 1914.

Application filed July 9, 1908. Serial No. 442,769.

To all whom it may concern:

Be it known that we, WILLIAM H. LANE and ALBERT V. T. DAY, citizens of the United States, residing at Westfield, county 5 of Union, and State of New Jersey, and New Rochelle, in the county of Westchester and State of New York, respectively, have invented a certain new and useful Improvement 10 in Electric Traffic-Controlling Systems for Railroads, of which the following is a specification, reference being had therein to the accompanying drawings, forming part thereof.

Our invention relates to electric traffic-controlling systems for railroads of the type 15 in which the signals or other traffic-controlling devices are automatically controlled through the action of a train or railway vehicle on a circuit including the track rails.

20 In some systems of the type referred to it is necessary or desirable, particularly in the case of electric railways, to use continuously conductive track rails which may serve as conductors for traction current or for other currents, and in such cases, since the several track circuits of the traffic-controlling system cannot be isolated from each other in the ordinary manner by the interposition of insulated joints in the rails, this isolation 25 of the track circuits must be accomplished in other ways.

The chief object of the present invention is to produce a system in which this is accomplished in a novel and effective manner, 35 so that track circuits formed in closely adjacent portions of the rails may control their appropriate relays or other electro-responsive apparatus in an efficient and reliable manner without interference with each other.

40 One feature of our invention consists in the use, in a system of the type above referred to, of track circuits formed in continuously bonded track rails and including heavy cross-bonds of low resistance and impedance, these cross-bonds being utilized as members of transformers by which the alternating or periodic currents in the track circuits operate inductively upon the relays controlled thereby.

45 Another feature of the invention consists in the use, in conjunction with such cross-

bonds, of means applied to the track rails between the points of connection of adjacent cross-bonds, to increase the impedance of the rails at these points so as more effectively 55 to confine the currents in the rails to their appropriate paths and thus to more effectively isolate the track circuits.

Other objects and features of the invention will be apparent from the following 60 description of the illustrated embodiment thereof.

We will now describe the embodiment of our invention illustrated in the accompanying drawings, and will thereafter point out 65 the invention in claims.

Figure 1 of the drawings is a diagram of a portion of a block signal system embodying our invention, showing one complete block and portions of the two adjacent 70 blocks. Fig. 2 is a horizontal sectional detail view of one of the track transformers constituting cross-bonds, and Fig. 3 is a vertical section of the same. Fig. 4 is a side elevation, and Fig. 5 a transverse section, 75 of a portion of one of the track rails with impedance devices applied thereto.

The two signal stations shown in the drawings are designated respectively as B and C. In the following description the 80 station next to the right of B, which is not shown, will be called "station A." Similar parts of the apparatus at the several stations are designated by similar reference numbers, but in the description the numbers 85 are followed, where necessary, by letters to indicate at which station the part referred to is located.

The illustrated embodiment of the invention is particularly applicable to electric railroads in which the track rails are used as conductors for traction current, and the drawings represent continuously bonded track rails 1 suitable for this purpose. The track is divided by the signals into blocks, 95 and at or near the middle of each block the rails are connected respectively with the terminals of the secondary winding of a transformer 2 energized through transmission wire 3 by a suitable alternating generator 4. Near the right-hand end of each block is a cross-bond, such as 5 or 5B, and 100

near the left-hand end is a cross-bond, such as 6 or 6B. The rails and the cross-bonds form a divided track circuit in each block, which, starting at the transformer terminal 5 connected with one rail, passes in both directions through this rail to the cross-bond at the ends of the block, through the cross-bonds to the other rail, and back through the latter to the transformer. The track circuits control the signals through the inductive action of the current in the cross-bonds 10 5, 6, 5B and 6B. These bonds are short and heavy so as to act efficiently as cross-bonds for traction current, but they are utilized 15 as the primary windings of transformers of which the secondary windings 7 are connected with relays 8 and 9 at each signal station, and these relays control the line circuits through which the signals are controlled. 20 The relays are of the polarized alternating-current type. Each relay has a field magnet constantly energized by connection, through feed wires 10 and 11, with the secondary winding of a transformer 12 at each 25 station. The transformers are energized by connection with the transmission wires 3. Each relay has a pivoted armature 13 controlling a contact finger 14 or 15, and the armature is provided with a coil connected 30 with one of the transformer secondaries 7. So long as both field magnet and armature coil are energized by currents of the same frequency and in proper phase relation, the contact finger is maintained in raised position 35 against a coöperating fixed contact; but when the armature coil is deenergized or energized with current of opposite phase, the contact finger falls and opens the line circuit. 40 The line circuit through which the signal at station B is controlled passes from feed wire 11C through line wire 20 to signal 19B, thence through contact finger 14 and fixed contact of relay 8B to line wire 17 and back 45 through this line wire to station C, through the fixed contact and contact finger 15 of relay 9C, and thence to feed wire 10. With the apparatus in normal position, as illustrated, this line circuit is closed and current 50 from feed-wires 10 and 11 constantly energizes the electric operating device of signal 19B, which may be of any ordinary or suitable character so as to maintain the signal normally cleared. The signal has, however, 55 a normal bias to danger position, and when the line circuit is broken by either of the relays 8B or 9C the signal goes at once to danger position. 60 The action of a train in entering a block is to short-circuit the track circuit. As the train enters the right-hand end of the block B-C, it short-circuits the right branch of the circuit and thus cross-bond 5B and relay 8B are deenergized, and the line circuit is

broken by relay 8B. The signal 19B thereupon goes to danger position behind the train. When the train reaches the left-hand portion of the block, the same condition is maintained through the deenergization of relay 9C due to short-circuiting of track current from the cross-bond 6C, the line circuit being held open at relay 9C until the train leaves the block B-C. 65 70 75

The isolation of the adjacent track circuits, comprising cross-bonds such as 5 and 6 or 5B and 6B, at each station, is effected in two ways. In the first place, the cross-bonds are separated from each other by a short distance which is limited by conditions of practice to about thirty (30) feet, but which affords a length of rail having sufficient natural impedance to cause the currents to flow by preference through the cross-bonds which are made of negligible or small impedance for this purpose. In other words, the cross-bonds which act as transformer primaries have such a small or negligible resistance and impedance that the current supplied by the transformer of a given block will not flow beyond the cross-bonds at the ends of that block in sufficient degree to interfere with the proper operation of the system. Thus the transformer cross-bonds have the effect of fixing the limits of their respective blocks or sections and 90 it is this effect or characteristic of the transformer cross-bonds which is hereinafter referred to in the expression "block limiting" or "section limiting" cross-bonds. The latter, although serving as primary windings in the track transformers, are very short and heavy and are of such low resistance and impedance that each bond acts practically as a short circuit with respect to the intervening rails and the adjacent cross-bond. In the second place, the short-circuiting action of the bonds on the natural impedance of the intervening portion of the rails is not depended upon alone, in the preferred embodiment of the invention, to accomplish the isolation of the track circuits, but devices are applied to the rails between the adjacent short-circuiting cross-bonds to increase the impedance of the intervening rail portions. 105 110 115

In the specific construction of the track transformer shown in Figs. 2 and 3, which is adapted to be located between the rails, the cross-bond 5 consists of a heavy bar which makes one turn and one-half about a 120 laminated iron core 22 of the "iron-clad" type. The ends of the bond are connected directly to the rails and are provided with elbows 23 to afford sufficient flexibility. The secondary winding 7 is in the form of a 125 coil of many turns surrounding the convolution of the cross-bond.

In Fig. 3 the cross-bond acting as the

primary of the transformer passes from the terminal elbow connected with the lower rail, underneath the secondary coil 7, thence through the transformer core 22 in a straight length 5 of square cross-section (as shown in Fig. 3), thence across the end of the core in a short length 5^a, which tapers from the square cross-section to the flat or oblong cross-section of the straight length 5^b, in which the bond is continued back through the other channel of the core to the short length 5^c passing across the starting end of the core and tapering back to the square cross-section 5^d (cut away in Fig. 2), which passes again through the core, over the first square length 5, and direct to the opposite terminal elbow. The bonds shown at the signaling station B are slightly different in that they constitute only a single length of primary conductor in the transformers, passing direct from rail to rail directly through the channel of the transformer core which is not separately illustrated, since it will be substantially the same as the core 22 of Figs. 2 and 3 except that the core section 22^a (Fig. 3), which incloses the return primary strip 5^b, will be omitted.

The means for increasing the impedance of the rails, as shown in Figs. 4 and 5, comprise plates 24 and 25 of iron, which are fastened to the inside and the outside of the rail by means of bolts 26. These plates surround the rail, with the exception of its head, so as to form a substantially complete magnetic circuit about the body of the rail. The plates are applied in short lengths, which may be inserted between the ties upon rails already spiked in place, and they preferably are insulated from the rails sufficiently to prevent diversion of current from the rails to the plates. For this purpose it is sufficient to enamel the plates. The current is thus confined to the rails themselves, and as these are nearly surrounded by iron magnetic circuits, their impedance is increased to a degree sufficient to substantially facilitate the operation of the signal apparatus, without, however, substantially impairing the rails as conductors of traction current, either direct or alternating.

In case either cross-bond at a station should be accidentally broken, the current normally flowing through that bond, as a portion of a track circuit, may be diverted to the adjacent bond, and it is necessary to provide that such current may not operate to actuate the corresponding relay in the same manner as current from the proper source. To this end the transformers 2 are connected with the rails in opposite sense at alternate blocks. Thus, transformer 2 in block A—B is connected oppositely to the transformer 2 in block B—C, as shown in the diagram. If cross-bond 6B breaks, cur-

rent from the transformer in block A—B 65 may flow through cross-bond 5B. As this current is opposite in phase to the current normally flowing in the cross-bond 5B, it acts to rotate the armature of relay 8B in a direction to open the line circuit, and thus 70 to set signal 19B at danger position. If cross-bond 5B breaks, a similar action occurs in cross-bond 6B and relay 9B, thereby setting the signal at A at danger.

Various modifications may be made in 75 the embodiment of the invention hereinbefore described and illustrated in the accompanying drawings, within the nature of the invention and the scope of the following claims. 80

We claim:

1. A traffic-controlling system comprising, in combination with continuously conductive track rails, two transformers of which the primary windings are connected 85 across the rails, means for energizing with periodic currents the track circuits formed by the rails and said windings, means for increasing the natural impedance of the rails between the points of connection of 90 said windings, and electric traffic-controlling means connected with the secondary windings of said transformers.

2. A traffic-controlling system comprising, in combination with continuously conductive 95 track rails, two transformers of which the primary windings are connected across the rails at adjacent points and constitute section-limiting cross-bonds of low impedance, means for energizing with periodic currents 100 the track circuits formed by the rails and said section-limiting windings, electric traffic-controlling means connected with the secondary windings of said transformers, and means for increasing the natural impedance of the rails between the points of connection of said windings. 105

3. A traffic-controlling system comprising, in combination with continuously conductive track rails, two transformers of which the primary windings are connected across the rails at adjacent points and constitute section-limiting cross-bonds, means for energizing with periodic currents of opposite phase the two track circuits formed by the 110 rails and said windings, means for increasing the natural impedance of the rails between the points of connection of said windings, and polarized relays connected with the secondary windings of said transformers. 115

4. A block signal system comprising, in combination with continuously conductive track rails, transformers of which the primary windings are connected across the rails 125 near the ends of the blocks or sections and constitute section-limiting cross-bonds of low impedance, means for energizing with

periodic currents the track circuits formed by the rails and said windings, means for increasing the normal impedance of the rails between the points of connection of said windings, and signal-controlling relays connected with the secondary windings of said transformers.

In testimony whereof we have affixed our signatures in presence of two witnesses.
